(No Model.)

A. W. PUTMAN-CRAMER.

METHOD OF PRODUCING GAS.

No. 323,366.

Patented July 28, 1885.

Inventor:
Anthon W. Putman-Cramer
by his Atty.
Brown & Hall

UNITED STATES PATENT OFFICE.

ANTHON W. PUTMAN-CRAMER, OF BROOKLYN, NEW YORK.

METHOD OF PRODUCING GAS.

SPECIFICATION forming part of Letters Patent No. 323,366, dated July 28, 1885.

Application filed October 30, 1884. (No model.)

To all whom it may concern:

Be it known that I, ANTHON W. PUTMAN-CRAMER, of the city of Brooklyn, in the county of Kings and State of New York, have invented a new and useful Improvement in the 5 Method of Producing Gas, of which the following is a specification.

My invention relates to the production of gas by the decomposition of steam or water in 10 the presence of carbon, whereby there is produced a mixture composed mainly of hydrogen and carbonic oxide, which may have added to it hydrocarbon vapor to form an illuminating gas, or be used without the addition of such 15 vapor as a heating gas.

My invention consists in an improvement in the method of making gas by the decomposition of water in presence of carbon, consisting in subjecting a body of carbon to the influence of currents of air to produce combustion therein, mingling air with the carbonic oxide evolved from the said body of carbon, heating another body of carbon by the burning of the mixture of air and carbonic oxide, 20 and passing steam directly to and through 25 both bodies of carbon simultaneously, whereby both bodies of carbon are made effective in decomposing steam.

In the accompanying drawings, Figure 1 is 30 a vertical section of an apparatus for carrying out my improved method. Fig. 2 is a side elevation thereof. Fig. 3 is an end elevation thereof; and Fig. 4 a horizontal section on the plane of the dotted line $x-x$, Figs. 1 and 2.

Similar letters of reference designate corresponding parts in all the figures.

The apparatus may be built of fire-brick or other refractory material, inclosed in a shell or casing of plate-iron, as is usual in structures of this class.

A A' designate two chambers, which are separated in part by a wall or partition, A*, which may be strengthened by a metal plate, a , or in any other suitable manner. In the chamber A A' are grates b b' , and B designates a chimney which communicates with the chamber A' at c , below the grate b' therein. The top of the chimney B is closed by a valve, d , which, as shown, is carried by an arm, d' , on a rock-shaft, d^2 . On said shaft is a pulley or sheave, d^3 , and by means of a chain or other connection, d^4 , passing over guide-pulleys d^5 ,

and to a point within reach of the attendant, the valve d may be raised and opened or closed. At the top of the chambers A A' are feeding- 55 apertures e , closed by lids or covers e' , having a sand or other air-tight seal. I have shown each chamber A A' as having below its grate and on opposite sides apertures or openings f , for cleaning, and above the grate and on 60 opposite sides throats or openings g , for emptying the chambers when desired. These are all to be closed by suitable doors. (Not here shown.)

C designates a main air or blast pipe, which 65 may lead from a fan, blower, or other suitable blowing apparatus, and C' designates the valve which controls the passage of air from this main pipe C through branch pipes C², extending on opposite sides of the apparatus. 70 The branch pipes C² are connected at h with the throats or openings j of the chamber A, and are thence extended upward to a point above the grate b' in the chamber A', (as here shown, near the top thereof,) where they communicate 75 with and supply air to the chamber A' through one, two, or more tuyeres, h' , two being here shown.

D designates the main steam-pipes, from 80 which branches D' extend on opposite sides of the apparatus, and these branches communicate at several points, i , with the chambers A A', below the grates therein.

E designates the pipe through which the 85 gas is conducted from the apparatus.

In the operation of the invention the chambers are both filled to the desired height with carbonaceous material, and the valve d being opened and the valve in the gas-outlet pipe E closed, air is admitted through the pipes C² and 90 branches or tuyeres h' to the chamber A below the grate and the chamber A' above the grate. The oxygen of the air in passing upward through the fuel in the chamber A combines 95 with the carbon and produces carbonic oxide, which is ignited when it meets the air entering through the tuyeres h' , and the heat resulting from the combustion of the carbonic oxide in passing downward in the chamber A' heats the carbon contained therein. When 100 deep fires are run in the chambers the tuyeres h' are immediately above the fire in the chamber A', and the air there entering mingles with the carbonic oxide and produces combustion

in the mass of fuel in the chamber A'. The combustion of the carbonic oxide in the chamber A' renders the latter far more effective in heating the carbon in that chamber, and hence 5 the supply of air to the chamber A does not have to be continued long after the carbon therein has reached a decomposing temperature in order to bring the carbon in the chamber A' to that temperature. It will be seen, 10 therefore, that an important saving in fuel is effected by my invention.

When the carbon in both chambers reaches a decomposing temperature, the air-valve C' is closed, the valve d is also closed, and the valve 15 in the gas-outlet pipe is opened. Steam is then introduced at i, and, passing upward through the incandescent fuel, is decomposed, and the gas, consisting mainly of hydrogen and carbonic oxide, is taken off through the 20 pipe E. When the fuel in the chambers cools so as to render decomposition imperfect or impossible, the admission of air is repeated and the operation carried out as before.

The steam will be converted into gas composed 25 mainly of hydrogen and carbonic oxide by passing through one body of carbonaceous material of sufficient depth, and by using both bodies of carbon simultaneously, for purposes of decomposition, I enable a very great volume 30 of gas to be produced in an apparatus of comparatively small size.

I am aware that in apparatus heretofore made it has been customary to employ two bodies of heated carbon and to pass steam first through 35 one body of carbon, whereby it is decomposed,

to then add hydrocarbon vapors to the products of decomposition and to pass the mixture through the second body of fuel. By such method the volume of gas produced only equals the capacity of the first body of carbon 40 for decomposition.

My method differs essentially from the above, in that I pass steam directly to and through both bodies of carbon simultaneously, and decomposition is being effected simultaneously 45 by both bodies; hence, with two bodies of carbon of equal size and temperature, I can decompose about twice the volume of steam and produce about twice the volume of gas that is possible by the old method. 50

What I claim as my invention, and desire to secure by Letters Patent, is—

The improvement in the method of making gas by the decomposition of water in presence of carbon, consisting in subjecting a body of carbon to the influence of currents of air to produce combustion therein, in mingling air with the carbonic oxide evolved from the said body of carbon, in heating another body of carbon by the burning of the mixture of air 60 and carbonic oxide, and in passing steam directly to and through both bodies of carbon simultaneously, whereby both bodies of carbon are made effective in decomposing steam, substantially as herein described. 55

A. W. PUTMAN-CRAMER.
